APPARATUS FOR DETECTING STRAIN IN
GLASS OF A PARTIALLY DIFFUSING
CHARACTER

Samuel M. Gray, Yonkers, N. Y., assignor to Electrical Testing Laboratories, New York, N. Y., a corporation of New York

Application April 22, 1932, Serial No. 606,851

4 Claims. (Cl. 88—14)

The present invention relates to apparatus, commonly referred to as polariscopes, for detecting strains in glass. The invention is particularly concerned with the detection of strain in frosted glass (clear glass having an irregular surface produced by acid etching or sand blasting) and opalescent or lightly flashed opal glass (clear glass having on one of its surfaces a flashing of opal glass). The invention may be applied to any 10 clear glass having a surface or thin film of a light-diffusing character.

Strains in glass are largely due to improper annealing or too rapid cooling, the most typical of all annealing strains being those arising from 15 the fact that the outside surface of the glass cools before the inside surface. In the manufacture of electric lamps, strains in the glass bulb are liable to occur as a result of improper blowing or cooling. However, strains of a more serious 20 character and more frequent occurrence have their origin subsequently to the manufacture of the lamp proper, when annealing a comparatively small portion of the bulb for a reason which will be presently understood. It is desirable to mark 25 or characterize the finished lamp with reference to its make or the manufacturer's trade-mark and with reference to its rated voltage and wattage. The usual procedure for such marking of the lamp consists in stamping the marks in ink 30 on the bulb, thereafter subjecting the marked portion to a fixing process consisting in the application of a flame to said marked portion, and finally slowly cooling the bulb to room temperature. If this heating and cooling is not carried out with care, comparatively severe strains 35 may be produced in the portion of the glass so treated.

Besides the disadvantage that lamp bulbs are rendered more susceptible to breakage if strains 40 are present in the glass, necessitating increased precaution in handling the lamps, strains become of a dangerous nature when present in the bulbs of gas filled lamps. As is well known, upon breakdown or rupture under service of the filament of a gas-filled lamp, an arc may be set up through the gas within the envelope, which arc is generally heavy enough to cause the melting 45 of those portions of the filament which are bridged over by the arc. As the resistance of the circuit decreases, the strength of the arc steadily increases, with the result that the complete extent of the filament and its supporting 50 electrodes leading thereto may be caused to melt. Should this hot fused metal strike an envelope 55 in which a strain is present, the impact as well

as the sudden increase in temperature of the envelope may cause the latter to break with an attendant explosion of great violence. It is thus desirable that electric lamps be tested for glass strain prior to their being placed on the market.

The glass industry has generally adopted two polarization methods for detecting strain in glass, the one applying to the testing of clear or transparent glasses and the other applying to the testing of either transparent glasses or glasses 10 which are of a semi-opaque or light-diffusing character. The first of these methods offers no special difficulties, and, briefly stated, consists in viewing the specimen undergoing test between two polarizers which have their planes of polarization to light from a light source at right angles to one another and thus normally substantially prevent any light from being transmitted to the eye. Any birefringence as caused by strain in the specimen causes a depolarizing action on the light passing through the strained portion of the specimen, which lights up the field locally, giving both the location and an estimate of the magnitude of the strain. It is to be particularly noted that a diffuser such as a sheet of ground glass or 15 opal glass is required between the first polarizer and the light source, in order that the field in which the specimen is placed may be illuminated 20 uniformly.

Heretofore, this visual examination of the specimen has been considered impossible when working with translucent or light-diffusing glasses, which redirect the visible rays of the spectrum. Thus the method generally adopted for testing such glasses, which is the second of the methods 25 above referred to, utilizes the heat effect of the short infrared rays of the spectrum, which rays are capable of being transmitted without diffusion through either transparent or opaque glasses. The specimen is again interposed between two polarizers, but this radiation method requires additional apparatus of an expensive and delicate nature, such as a thermopile on which the rays which may pass through the second polarizer are concentrated and a galvanometer connected to the thermopile for indicating the strain by its deflection.

An object of the invention is to provide an apparatus of simple construction enabling visual detection of strain in glass of a partially diffusing character.

Another object of the invention is to provide an apparatus of simple construction for visually detecting strain in electric lamp bulbs of a partially diffusing character.

Still another object of the invention is to provide an apparatus of simple construction for visually detecting strain in either transparent bulbs of a partially diffusing character.

6 The invention will be clearly understood from the following description taken in connection with the accompanying drawings, in which—

10 Figs. 1 and 2 are schematic illustrations of embodiments of the invention; Fig. 3 is a vertical cross-sectional view through the central plane of an apparatus shown adapted for the testing of electric lamp bulbs of a partially diffusing character; Fig. 4 is a similar view of the same apparatus shown adapted for the testing 15 of transparent electric lamp bulbs; Fig. 5 is a fragmentary cross-sectional view of the apparatus taken on the plane indicated by the line 5×—5× of Fig. 3; Fig. 6 is a fragmentary front view of the apparatus, showing the rotatable disc 20 having the analyzer mounted therein; Figs. 7 and 8 are reproductions of actual photographs of bulbs of a partially diffusing character, taken under test.

I have made the important discovery that 25 glass having a surface or film of a light-diffusing character may be visually examined for strain between two polarizers having their respective planes of polarization to light at right angles to one another, by utilizing a light source of extremely high intensity and causing the rays 30 from the latter to be directly incident without diffusion, to the first polarizer. Thus, I omit the diffuser which has heretofore been considered essential between the source of light and 35 the first polarizer, so that, by this omission, I am able to cause a powerful beam of non-diffused plane-polarized light to issue from the first polarizer. With the specimen of the glass mentioned positioned for test in the path of such 40 beam, strain therein may, as I have found, be properly visually detected, notwithstanding the diffusion produced by the light-diffusing surface or light-diffusing film portion of the specimen. 45 On the other hand, this novel method of visually detecting strain in glass of the type referred to is made possible by the very nature of said surface or film portion, as said surface or film portion acts to even up the illumination of the visual field in which the strain appears. That is, 50 a field or background of uniform dimness is created in which any bright areas caused by strain in the specimen are made apparent to the eye by contrast therewith. The rays from the first polarizer pass through the specimen to the second polarizer without diffusion other than that 55 caused by the light-diffusing surface or light-diffusing film portion, but if the light source is of sufficiently high intensity, a substantial quantity of rays, as I have found, pass substantially undiffused through the light-diffusing surface or 60 light-diffusing film portion, because of which visual detection of strain in the specimen is made possible. For convenience in description hereinafter, the first and second polarizer will be 65 simply referred to as the polarizer and analyzer, respectively, these being the terms usually employed in the art for the two polarizers.

In Fig. 1 I have illustrated in simplified manner a means for carrying out the above method of strain detection. A powerful source of light 1 is placed at the principal focus of a converging lens 2 to produce a beam of parallel rays 4. In the embodiment illustrated a reflector, such as a 70 polished plate of black Carrara glass, is used as the

5 polarizer, which plate 5 is placed in the direct path of the powerful beam of light 4, the reflected rays 6 being plane-polarized with reference to their planes of reflection, or, since those planes are parallel in the embodiment illustrated, to the central plane of reflection (coinciding with the plane of the drawings). That is, the vibrations of each ray 6 are in a plane which may be conveniently assumed to be perpendicular to the plane in which it is reflected. Preferably, the angle of incidence α of the beam 4 to the plate 5 is made 10 equal to the polarizing angle of the substance of which the plate 5 is made. The polarizing angle of a substance is the angle of incidence causing maximum polarization and is equal to the angle the tangent of which equals the refractive index of the substance. For black Carrara glass, this polarizing angle is 56 degrees and 40 minutes. The analyzer, a Nicol prism 7 in the embodiment 15 illustrated, is placed in alinement with the plane-polarized rays 6. A Nicol prism is constructed from an elongated rhombohedron of Iceland spar cut into two parts along a certain plane, which parts are cemented together by Canada balsam. 20 Iceland spar is a double-refracting crystal, i. e., it gives rise under certain conditions to two refracted rays when a single light ray is incident thereto. One of these two refracted rays is called the ordinary ray and the other the extraordinary 25 ray, and the two rays are plane-polarized in planes at right angles to one another respectively. Referring to Fig. 1, first assuming that both ordinary rays and extraordinary rays are produced in the Nicol prism 7 by the beam of light incident 30 to the end face a of said prism upon entering said face, said prism acts to intercept all of the ordinary rays O by total reflection from the Canada balsam, but to permit the extraordinary rays E to pass and reach the eye, for the sake of clarity only one ordinary ray and one extraordinary 35 ray, corresponding to the center incident ray 8, being illustrated. It should be noted that the extraordinary rays E are plane-polarized at right angles to the principal planes of the prism taken with reference to its end faces a and b . 40 A principal plane of a crystal with reference to one of its faces may be defined as a plane which is drawn at right angles to that face and in which a ray of unpolarized light can proceed without double refraction or in which polarized light can travel without having its polarization disturbed. Thus, if the prism 7 be turned about the center 45 incident ray 8 as axis until its central principal plane with reference to its end faces a and b coincides with the central plane of reflection of the polarized rays 6 (the plane of the drawings), the planes of polarization with reference to which the analyzer 7 would polarize light assumed traveling therethrough are then perpendicular to the plane of the drawings or at right angles to the planes with reference to which light from the source 1 is polarized by the reflector 5. For this position of the analyzer (assumed to be 55 the case in Fig. 1), it is set to reject the larger portion of the light that the polarizer 5 sends forward. That is, no extraordinary rays E are theoretically capable of production and the ordinary rays O are lost by total reflection, so that 60 minimum illumination of the visual field is produced.

Now, as I have discovered, it is possible to detect strain in a specimen such as the plate 9 having a surface or film 11 of a light-diffusing character, by interposing it between the polarizer 5 and 70

the analyzer 7 in the path of the powerful beam of plane-polarized rays 6. Strained glass is birefringent, i. e., it acts as a double-refracting crystal under the influence of light. Thus, a strain in the specimen causes a change in the character of those rays 6 which travel through said strain. This change is generally believed to be a transformation of the plane-polarized light leaving the polarizer into elliptically-polarized light. Whatever may be the nature of the change, rays E are transmitted to the eye and the field is illuminated locally, the illuminated portions corresponding to strained portions of the glass. It is to be particularly noted that successful examination of the specimen 9 is made possible by omitting the usual diffuser between the source 1 and the polarizer 5 and by illuminating the polarizer 5 by properly directed rays from the powerful light 4. Any reflection or refraction suffered by polarized light changes its plane of polarization. Thus, should the polarizer 5 be illuminated by diffused light, the specimen 9 would likewise be illuminated by diffused light and, because of the diffusing power of the surface or film 11, much of the light reflected by the polarizer 5 in the direction of the analyzer 7 would be redirected elsewhere and much of the light reflected by the polarizer 5 in other directions would be redirected toward the analyzer 7 after suffering considerable deviation and change in plane of polarization, the net result being depolarization of the light incident to the analyzer 7. On the other hand, by so directing the rays from the source 1 as to cause them upon transmission from the polarizer 5 to normally all proceed in a general direction toward the analyzer 7, the light incident to the analyzer 7 suffers a minimum of reflection or refraction when passing through the surface or film 11. As I have found, if the source 1 is of sufficiently high intensity, substantially undepolarized light is forced through the surface or film 11 in quantity sufficient to have the proper detecting action in the visual field on any strain in the specimen. It is to be particularly noted, however, that this strain detection is actually permitted by the surface or film 11, because of the diffusing power of which all rays reaching the analyzer and composing the visual field are made uniform in intensity, acts to even up both location and magnitude of strain (by its degree of illumination) being therefore made distinctly observable in the visual field. I have found it possible to detect strain in the specimen whether positioned, as in Fig. 1, with the plane-polarized rays 6 incident to its light-diffusing surface or light-diffusing film portion 11, or reversed from its position shown in said figure, with said rays 6 incident to its transparent portion or to the glass proper.

With the analyzer 7 positioned in the path of the reflected rays as in Fig. 1, light is to a certain extent transmitted through the analyzer 7 to the eye under any conditions, even with the specimen 9 removed from the apparatus. The greater the intensity of the source 1, the greater is the amount thus transmitted. Moreover, the amount transmitted is appreciably increased when a tint-producing element (to be hereinafter described) is interposed between the specimen and the analyzer. This transmitted light, although not effecting detection or visibility of strain because of the uniform illumination of the field which results from the light-diffusing sur-

face or light-diffusing film portion of the specimen, becomes particularly objectionable, in view of its intensity and the resulting harm to the eye, when the specimen is removed from the line of vision, no light-diffusing means being then present anywhere along the path of travel of the light from the powerful source 1. Now, I have found it possible to view the specimen under study at an angle with the direct path of the rays sent forward by the polarizer, so that none of these rays are incident to the analyzer and none therefore conducted directly to the eye. A clear determination of any strain is nevertheless made possible by reason of the intense illumination of the specimen.

This indirect method of viewing the specimen is illustrated in simplified manner in Fig. 2, and is the method I prefer when testing such specimens as electric lamp bulbs of frosted glass or the like. The apparatus includes the same elements as in Fig. 1, but here the analyzer 7 is shown as having been rotated 180 degrees about an axis 12, making an angle with the center reflected ray 8, to bring the line of vision out of the direct path of the reflected rays 6. The specimen 14, shown as an electric lamp bulb having an inner surface or film 16 of a light-diffusing character, may thus be conveniently held in the hand and turned into various positions in the path of the reflected rays 6 to permit its entire extent to be examined from one portion to another, without danger to the eye from the direct rays which may travel past said specimen unobstructed or unintercepted by said surface or film 16. By its 180 degree rotation, the analyzer 7 again has its central principal plane with reference to its end faces *a* and *b* coinciding with the central plane of reflection of the rays 6. As in Fig. 1, therefore, the polarizer 5 and the analyzer 7 have their respective planes of polarization to light at right angles to one another, so that minimum light is normally transmitted to the eye.

The intensity of the light I permits rays 6 to travel through both rear and front walls of the bulb 14, so that the entire extent of said bulb is brilliantly illuminated. As has already been explained, light rays 6 undergo a certain change when passing through a strained portion of a specimen. I have discovered that this effect is transmitted to the indirect rays, such as 15, travelling from the specimen 14 to the analyzer 7 in Fig. 2. That is, a change in the character of the light is also effected on these indirect rays, when issuing from a strained portion of the specimen 14, so that light E' is correspondingly locally transmitted through the analyzer, rendering the strain visible to the eye. It should be noted that there are two portions of the bulb located on the line of vision, so that there are actually two portions under observation at any time. Thus, the bulb 14 should be manipulated into various positions to make sure that a single strain is visualized at one time, and not two superimposed strains which might appear to the eye as a single strain. In general, however, a single strain appears, which strain, for reasons already advanced, is in the end portion c of the bulb, whereon the manufacturer's stamp is located. In Fig. 2 this end portion c is shown under observation, it being understood that bulbs having an outer surface or film of a light-diffusing character may be similarly tested.

The tint-producing element 17 shown disposed in the path of the rays to the analyzer 1 in Fig. 2, consists of a thin crystalline plate or disc of a

double-refracting crystal, such as selenite, having its principal planes set at 45 degrees to the central plane of reflection of the plane-polarized rays 6 proceeding from the polarizer 5. This thin crystal 17 may be conveniently held between two plates or discs 19 of unstrained optically plane transparent glass. It acts to effect elliptic polarization of the plane-polarized rays incident thereto, due to the fact that the ordinary and extra-
10 ordinary components produced by the splitting up of the plane-polarized rays, which components have their respective planes of vibration at right angles to one another, are unequally retarded, i. e., their velocities are different, when passing
15 through the crystalline plate. The elliptically-polarized rays emerging from the crystalline plate 17 give rise to two sets of rays when entering the Nicol prism. One set, the ordinary rays O', are extinguished by total reflection, as previously ex-
20 plained, and the other set, the extraordinary rays E', are transmitted to the eye. These transmitted rays are made up of components of both ordinary and extraordinary rays produced by the crystalline plate 17, these components being out of phase
25 with each other due to the retardation of one relative to the other in transmission through the selenite plate. This phase difference varies with the wave-length of the light. Consequently, when white light is used as the source 1, the relative
30 intensities of its component colors are changed when travelling through the Nicol prism, and therefore the transmitted rays E' will have a prevailing tint depending on the thickness of the plate. When using selenite, the field which is
35 usually caused to be produced is of a purplish color. If now a specimen of strained glass be introduced, it will have the effect of changing the phase difference of the superimposed ordinary and extraordinary rays transmitted through the
40 plate 17, with the result that the strain appears in colors contrasting with that of the field.

The apparatus illustrated in Figs. 3 and 4 may be utilized for testing either transparent bulbs or bulbs of a partially diffusing character, and I have designed this apparatus to permit it to be quickly altered to suit the particular test desired. This apparatus comprises an enclosing casing 20 having a base 21, side walls 22 (one being shown in Figs. 3 and 4 and the two in Fig. 5), a top plate 24, and a rear end cover 25. The latter is preferably hinged to the base 21 to provide access into the rear end portion of the casing. Two partitions 26 and 27 are inclined to one another and to the base 21, which partitions are each provided with an opening through which light may be transmitted. Each of the side walls 22 has a front edge portion parallel to the partition 26 and to which a front plate 29 is secured. The partitions 26 and 27 and the front plate 29 divide the casing into three compartments, the front compartment of which is opened at its bottom to permit insertion of the specimen and its manipulation in the path of the light rays, transmitted from the light source 32 in the rear compartment and reflected from the polarizer 28 in the middle compartment. The reflector 28 is fixed to the base 21 in any appropriate manner, and accumulation of dust particles on its polished surface is prevented by closing the opening in the partition 26 by a transparent plate of unstrained glass 30. If black Carrara glass is used for the reflector 28, the angle of the partitions 26 and 27 with the base 1 is preferably made equal to 56 degrees and 40 minutes, which is the polarizing angle of that substance, as already stated. The

light-transmitting apparatus located in the rear compartment is adjustably mounted on an inclined block 31 and comprises a lamp of high intensity, such as a 400 watt projection lamp, to which current is supplied by the cable 33, and a concave reflecting mirror 34, both the lamp and the reflector being adjustable in perpendicular directions relatively to the fixed block 31. A plurality of ventilation openings 35 may be formed through the top plate 34 of the casing.

When testing electric lamp bulbs of a partially diffusing character, I utilize an optical means, which may consist of a pair of plano-convex lenses 36 and 37 held in proper alignment in a frame 38, for directing a powerful beam of parallel rays to the polarizer 28 (as shown in Fig. 3). When testing transparent bulbs, this system of lenses is removed and I utilize a light diffuser 39 for the purpose of providing a uniformly bright background. This diffuser may consist of a sheet 20 of flashed opal glass held at its edges in a suitable frame 40 and, when properly positioned for a test on a transparent bulb, completely covers the opening formed through the partition 27 (as shown in Fig. 4).

To facilitate this interchange of parts, the system of lenses 36 and 37 and the diffuser 39 are each made slidable in a separate plane. Thus, the frame 40 holding the light diffuser is guided between the partition 27 and suitable strips 41 secured to the side walls 22 of the casing 20 (Fig. 5), while the frame 38 holding the system of lenses is provided with side flanges 42 (Fig. 5), which slidably cooperate with guides or strips 44 also fixed to the side walls 22 of the casing 20. A pair of chains 45 is attached at one end to the sides of the frame 40 and at the other end to the sides of the frame 38, each of said chains 45 meshing with a sprocket wheel 46 fixed to a shaft 47 journaled in suitable bearing supports 49 depending from the top cover plate 24. The shaft 47 has one end projecting through one of the side walls 22, and to this end is attached a crank 50 by means of which the shaft 47 may be rotated. Thus, a rotation of the crank 50 in a clockwise direction will raise the light diffuser 39 out of the way and lower the system of lenses 36 and 37 into operative position (Fig. 3), and a counter-clockwise movement of the handle 50 will raise the system of lenses and lower the light diffuser (Fig. 4). Suitable stops 51 and 52 are provided for limiting the downward movements of the light diffuser and of the system of lenses, respectively.

A disc 54 (Fig. 6) is rotatably mounted on an inclined block 55 fixed to the front plate 29 of the casing 20, and into an opening formed through this disc 54 is fitted a tubular protective casing 55' for a Nicol prism 56 and a thin sheet of selenite (held between glass plates 57). The axis of rotation of the disc 54 is at an angle to the path followed by polarized light from the reflector 28, and at one side of this axis there is an opening 59 formed through the plate 29 and the block 55 in alignment with the center ray (58 in Fig. 3 and 58' in Fig. 4) of such light. This opening 59 is in registration with the disc opening when the disc is rotated into the position shown in Fig. 4. There is another opening 60 formed through the plate 29 and the block 55 at the other side of the axis of rotation, which opening 60 is in registration with the disc opening when the disc is rotated 180 degrees from its position shown in Fig. 4 into the position shown in Fig. 3.

Thus, in Fig. 3, the line of vision through the analyzer 56 is out of alignment with the powerful

beam of polarized light, which is caused to be established by employing the system of lenses 36 and 37, such specimens as the inside frosted bulb 62 shown being visually examined, as heretofore explained, by means of the indirect rays, such as 61, transmitted therefrom to the analyzer. In Fig. 4, the line of vision through the analyzer 56 coincides with the center ray 58' of polarized light so that, with the diffuser 39 properly interposed in the path of the rays from the lamp 32, such specimens as the transparent bulb 63 shown may be visually examined, in the usual manner, by means of that part of the light sent forward by the diffuser 39 which is reflected at the polarizing angle by the reflector 28. It is noted that in both positions of the Nicol prism 56, its central principal plane coincides with the central plane of reflection, and that in both positions of the selenite crystal, its central principal plane is set at 45 degrees with the central plane of reflection, tests on either transparent specimens or specimens of a partially diffusing character being thus possible without any change in the position of the prism or of the selenite crystal, except that produced by a rotation of the disc 54. All that is required for an interchange of test is a rotation of the crank 50 and a rotation of the disc 54.

Fig. 7 is reproduction of an actual photograph of a typical so-called "Maltese" cross-shaped strain in the end portion of an inside frosted lamp, as revealed by the apparatus of the invention. This photograph was taken with a panchromatic plate, with the tint-producing element or selenite crystal removed from the polariscope to obtain in the first instance a visual effect in black and white and therefore to permit the camera to receive a true record of the dark and bright portions of the specimen under test. Also, in order to visualize more clearly the effect of strain, I removed by crocus cloth the manufacturer's stamp which was located on the very end portion of the bulb where the strain occurred as revealed by the polariscope. As shown in the figure, four bright spots, 70 and 71, were caused to appear, separated by a dark cross 72. The cross had the characteristic blackness of the field 74 in which the specimen was visualized, but this does not indicate that the stresses were zero in the cross. It should be observed that the stresses in glass are apt to be oriented in different directions in different places, and that plane-polarized light is not affected, when passing through a strained portion, if the planes in which the light rays are vibrating are parallel to or at right angles to the stress. To obtain a maximum effect on the plane-polarized light, its plane of polarization should be at 45 degrees to the stress. Thus, the stresses in the end portions of the cross 72 were no different in magnitude from those in the bright spots 70 and 71, but the stresses in one set of oppositely disposed end portions and those in the other set were respectively parallel and at right angles to the plane-polarized light in which the specimen was examined, neither one of these end portions therefore being capable of effecting a change in such light and capable of having much light transmitted therefrom through the analyzer. On the other hand, the plane-polarized light did undergo a change, probably elliptic polarization, upon travelling through the strained portions where the bright spots (70 and 71) appeared, the orientation of the stresses in such portions being such as to permit their illumination. At the center of the cross 72, there was a considerable dark area. Actually, the strain was maximum at

this center portion, but as it was equally oriented in all directions, it could not be made to appear in the polariscope. The investigator thus uses precaution in the setting of a specimen in the path of the plane-polarized rays, so as not to overlook the stresses altogether, as well as in interpreting the results obtained. With the selenite crystal inserted in the polariscope, the color effect was as follows: The field 74 was purple and the cross 72 was of a purplish hue. A blue color prevailed in one set (70) of diagonally disposed spots, indicating such orientation of stress as to have caused an increase in the phase-angle of the two component vibrations of the elliptically-polarized light issuing from the selenite crystal. A red color prevailed in the other set (71) of diagonally disposed spots, indicating such orientation of stress as to have caused a decrease in the phase-angle of the two component vibrations of the elliptically-polarized light issuing from the selenite crystal.

Fig. 8 illustrates the effect produced by photographing a so-called ring-shaped strain in another inside-frosted lamp under test in the apparatus of the invention. In this test, the selenite crystal was properly positioned in the path of the rays to the camera, and the photograph was taken with an orthochromatic plate (sensitive to blue). It should first be noted that this photographic effect is vastly different from the colored effect as it actually appeared to the eye. Here the stresses were so oriented as to cause a circular colored band concentric with the central portion 80 where the manufacturer's mark is located, the color red prevailing in the oppositely disposed segments 81 and the color blue prevailing in the other oppositely disposed segments 82. The red color of the portions 81 is the reason why they show dark in the reproduced photograph. Although the central portion 80 appears bright in the illustration, its color to the eye was of the characteristic purple of the field 83. This again does not indicate that the stresses were zero at the center. As a matter of fact the center was under the severest strain, but as the stresses were oriented in all directions, substantially no change was effected in the plane-polarized light transmitted through it.

The bright spots located at the rim of the two specimens in Figs. 7 and 8 were not strains in the glass, but were caused by reflection of light from the side portions of the bulbs.

It is understood that the apparatus described herein is subject to various modifications without departing from the spirit of the invention.

What is claimed is:

1. An apparatus for visually detecting strain in glass having a surface or film of a light-diffusing character, comprising a source of light, optical means for directing rays from said source in the form of a non-diffused beam of light, a polarizer to which said beam is incident, and an analyzer adapted for movement into either of two operative positions corresponding to which the lines of vision respectively established are in and out of the path of the polarized light proceeding from said polarizer, said source being of sufficiently high intensity to cause a substantial quantity of substantially undiffused rays to pass through the light-diffusing surface of light-diffusing film portion of the specimen undergoing test in said path and on either of said lines of vision, said polarizer and analyzer for either of said analyzer positions having their respective planes of polarization to light at right angles to one another.

2. An apparatus for visually detecting strain in glass having a surface or film of a light-diffusing character, comprising a source of light, optical means for directing rays from said source in the form of a non-diffused beam of light, a polarizing reflector to which said beam is incident, and an analyzing prism adapted for rotation about an axis inclined to the axis of the polarized beam proceeding from said reflector into either of two operative positions corresponding to which the lines of vision respectively established are in and out of the path of said polarized beam, said source being of sufficiently high intensity to cause a substantial quantity of substantially undiffused rays 15 to pass through the light-diffusing surface or light-diffusing film portion of the specimen undergoing test in said path and on either of said lines of vision, said prism in either of said positions having its planes of polarization to light at 20 right angles to those of said reflector.

3. An apparatus for visually detecting strain in either transparent glass or glass having a surface or film of a light-diffusing character, comprising a source of light, a polarizer for polarizing rays 25 from said source, light-diffusing means for use in carrying out tests on specimens of transparent glass, optical means for use in carrying out tests on specimens of glass having a surface or film of a light-diffusing character, said light-diffusing 30 means and optical means being each adapted for movement in and out of operative position with relation to said source, said light-diffusing means operating to diffuse the rays transmitted to said polarizer and said optical means operating to 35 direct the rays transmitted to said polarizer in the form of a non-diffused beam of light, and an analyzer adapted for movement into either of two operative positions corresponding to which the lines of vision respectively established are in 40 and out of the path followed by polarized light from said polarizer, specimens of transparent glass being positioned for test in said path and on the line of vision established in said path and specimens of glass having a surface or film of a 45 light-diffusing character being positioned for test in said path and on the line of vision established out of said path, said source being of sufficiently high intensity to cause a substantial quantity of 50

substantially undiffused rays to pass through the specimens of glass having a surface or film of a light-diffusing character, said polarizer and analyzer for either of said analyzer positions having their respective planes of polarization to light 5 at right angles to one another.

4. An apparatus for visually detecting strain in either transparent glass or in glass having a surface or film of a light-diffusing character, comprising a source of light, a polarizing plate 10 for polarizing rays from said source by reflection, light-diffusing means for use in carrying out tests on specimens of transparent glass, optical means for use in carrying out tests on specimens of glass having a surface or film of a light-diffusing character, 15 said light-diffusing means and optical means being adapted for movement in separate planes to permit movement of either in and out of operative position with relation to said source and also adapted for simultaneous movement in 20 opposite directions to permit movement of one into operative position with relation to said source simultaneous with movement of the other out of operative position with relation to said source, said light-diffusing means operating to diffuse the 25 rays transmitted to said plate and said optical means operating to direct the rays transmitted to said plate in the form of a non-diffused beam of light, and an analyzing prism adapted for 30 rotation about an axis inclined to the path followed by polarized light from said plate into either of two operative positions corresponding to which the lines of vision respectively established are in and out of said path, specimens of transparent glass being positioned for test in said path 35 and on the line of vision established in said path and specimens of glass having a surface or film of a light-diffusing character being positioned for test in said path and on the line of vision established out of said path, said source being of 40 sufficiently high intensity to cause a substantial quantity of substantially undiffused rays to pass through the specimens of glass having a surface or film of a light-diffusing character, said prism in either of said positions having its planes of 45 polarization to light at right angles to those of said plate.

SAMUEL M. GRAY.

CERTIFICATE OF CORRECTION.

Patent No. 2,073,690.

March 16, 1937.

SAMUEL M. GRAY.

It is hereby certified that error appears in the printed specification of the above numbered patent requiring correction as follows: Page 3, first column, line 50, strike out the words "acts to even up"; page 4, second column, line 75, for "alyzer" read analyzer; page 5, second column, line 3, after the word "investigator" insert must; and for "uses" read use; line 70, claim 1, for "of" read or; and that the said Letters Patent should be read with these corrections therein that the same may conform to the record of the case in the Patent Office.

Signed and sealed this 11th day of May, A. D. 1937.

2. An apparatus for visually detecting strain in glass having a surface or film of a light-diffusing character, comprising a source of light, optical means for directing rays from said source in the form of a non-diffused beam of light, a polarizing reflector to which said beam is incident, and an analyzing prism adapted for rotation about an axis inclined to the axis of the polarized beam proceeding from said reflector into either of two operative positions corresponding to which the lines of vision respectively established are in and out of the path of said polarized beam, said source being of sufficiently high intensity to cause a substantial quantity of substantially undiffused rays 15 to pass through the light-diffusing surface or light-diffusing film portion of the specimen undergoing test in said path and on either of said lines of vision, said prism in either of said positions having its planes of polarization to light at 20 right angles to those of said reflector.

3. An apparatus for visually detecting strain in either transparent glass or glass having a surface or film of a light-diffusing character, comprising a source of light, a polarizer for polarizing rays 25 from said source, light-diffusing means for use in carrying out tests on specimens of transparent glass, optical means for use in carrying out tests on specimens of glass having a surface or film of a light-diffusing character, said light-diffusing 30 means and optical means being each adapted for movement in and out of operative position with relation to said source, said light-diffusing means operating to diffuse the rays transmitted to said polarizer and said optical means operating to 35 direct the rays transmitted to said polarizer in the form of a non-diffused beam of light, and an analyzer adapted for movement into either of two operative positions corresponding to which the lines of vision respectively established are in 40 and out of the path followed by polarized light from said polarizer, specimens of transparent glass being positioned for test in said path and on the line of vision established in said path and specimens of glass having a surface or film of a 45 light-diffusing character being positioned for test in said path and on the line of vision established out of said path, said source being of sufficiently high intensity to cause a substantial quantity of 50

substantially undiffused rays to pass through the specimens of glass having a surface or film of a light-diffusing character, said polarizer and analyzer for either of said analyzer positions having their respective planes of polarization to light 5 at right angles to one another.

4. An apparatus for visually detecting strain in either transparent glass or in glass having a surface or film of a light-diffusing character, comprising a source of light, a polarizing plate 10 for polarizing rays from said source by reflection, light-diffusing means for use in carrying out tests on specimens of transparent glass, optical means for use in carrying out tests on specimens of glass having a surface or film of a light-diffusing character, 15 said light-diffusing means and optical means being adapted for movement in separate planes to permit movement of either in and out of operative position with relation to said source and also adapted for simultaneous movement in 20 opposite directions to permit movement of one into operative position with relation to said source simultaneous with movement of the other out of operative position with relation to said source, said light-diffusing means operating to diffuse the 25 rays transmitted to said plate and said optical means operating to direct the rays transmitted to said plate in the form of a non-diffused beam of light, and an analyzing prism adapted for 30 rotation about an axis inclined to the path followed by polarized light from said plate into either of two operative positions corresponding to which the lines of vision respectively established are in and out of said path, specimens of transparent glass being positioned for test in said path 35 and on the line of vision established in said path and specimens of glass having a surface or film of a light-diffusing character being positioned for test in said path and on the line of vision established out of said path, said source being of 40 sufficiently high intensity to cause a substantial quantity of substantially undiffused rays to pass through the specimens of glass having a surface or film of a light-diffusing character, said prism in either of said positions having its planes of 45 polarization to light at right angles to those of said plate.
